[57] CLAIM

The ornamental design for a oil lamp assembly, as shown and described.

DESCRIPTION

FIG. 1 is a perspective view of a oil lamp assembly showing my new design;

FIG. 2 is a perspective view of a second embodiment of my design;

FIG. 3 is a perspective view of a third embodiment of my design;

FIG. 4 is a side elevational view of the oil lamp assembly in FIG. 1;

FIG. 5 is a side elevational view of the second embodiment of my design shown in FIG. 2;

FIG. 6 is a side elevational view of the third embodiment of my design shown in FIG. 3.

The broken lines are shown for illustrative purposes only.

FIG. 1

FIG. 2

FIG. 3

FIG. 4

FIG. 5

FIG. 6
